UNITED STATES PATENT OFFICE.

WILLIAM W. BROWN, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

DYEING-MACHINE.

Specification of Letters Patent.

Patented Dec. 15, 1914.

1,120,899.

Application filed April 28, 1914. Serial No. 834,892.

To all whom it may concern:

Be it known that I, WILLIAM W. BROWN, a citizen of the United States, residing at Amsterdam, in the county of Montgomery and State of New York, have invented certain new and useful Improvements in Dyeing-Machines, of which the following is a full, clear, and exact description, such as will enable others skilled in the art to which it appertains to make and use the same.

This invention relates to dyeing machines, and with regard to certain more specific features thereof, to the so-called "trip mechanism," whereby the yarn-sticks are intermittently moved.

This invention has for one of its objects to provide a device of the character referred to which will operate effectively and which will be simple in construction, inexpensive to manufacture and durable in a high degree.

Another object of the invention is to provide a simple tripping mechanism adapted to automatically accommodate itself to several different conditions of dyeing machine operation.

Still another object of the invention is the provision of a durable trip which may be readily adjusted to resist different degrees of pressure.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of the various possible embodiments of the invention: Figure 1 is a view in perspective of a portion of a skein dyeing machine embodying this invention. Fig. 2 is a diagrammatic view of the trip as it appears in normal star-wheel tripping position. Fig. 3 is a diagrammatic view indicating the trip substantially in the position assumed when the star-wheel is not permitted to rotate, and the trip itself yields in compensation. Fig. 4 is a diagrammatic view of the trip indicating the positions assumed by the various parts as the star-wheel engages the trip in an opposite direc-

tion of rotation of the rotary spider or skein carrying frame.

Referring now more particularly to the drawing in which like characters of reference refer to similar parts throughout the several views, there is indicated at 1 a side wall of a housing in which there is mounted for rotation in any suitable manner a rotary spider 2. The spider 2 carries respectively at intervals around its periphery a plurality of square yarn-sticks, say twenty-five or thirty, one of which is indicated at 3. These yarn-sticks are not mounted directly in the spider 2, but preferably have reduced ends of an angular character which engage the angular walls of a cup, which in turn is mounted for rotation in the spider 2. This cup preferably has formed integral therewith a ratchet 4 and a star-wheel 5 having a plurality of fingers 6. A metal frame or skeleton 7 reinforces the housing on its outer side and secured to the outer side of this metal skeleton 7, as by means of the bolts 8 passing through slots 9, is a supporting member or bearing bracket 10. This bearing bracket is provided with suitable bosses, webs and bearings whereby it is adapted to support a shaft 11 extending through the upper portion thereof and loosely mounted therein. On the inner end of the shaft 11 there is fixed a trip member 12 having a lower bifurcated portion 13 which carries an anti-friction roller 14 adapted to rest normally in the path of travel of one of the fingers 6 of each of the star-wheels mounted upon the spider 2. This trip is secured to the shaft 11 and held against rotative or longitudinal displacement by means of the set-screw 15. On the outer end of the shaft 11 there is mounted a stop-member 16 also secured against rotary or longitudinal movement on the shaft 11 by means of a set-screw 17. This stop-member 16 has a depending rigid finger 18 and is recessed at 19 to accommodate the tongue 20 of a yielding finger 21. The yielding finger or member 21 is pivotally associated with the finger 18, as indicated at 22. Projecting from the lower end of the support 10 is a short stud 23 which serves as a fulcrum or pivot for a gravity controlled device, which, in the present embodiment, comprises a substantially long lever member 24 which in turn carries an

2

adjustable weight 25 adapted to be secured in different adjusted positions on the lever by means of the set-screw 26. At the upper end of this lever above the fulcrum or stud 23 there is formed a substantially short lug portion 27. The lever is adapted normally to hang by gravity so that the said lug portion 27 will rest in a position adjacent the stop-member 16, and the trip 12 and the stop-member 16 are adapted to be arranged on the shaft 11 so that by gravity the stop 16 will rest on one side of said lug member with the yielding finger 21 between the finger 18 and the said lug portion 27.

15. In the operation of this device, assuming the rotary spider 2 to be traveling in the direction of the arrow (Fig. 1), one of the fingers 6 of the star-wheel 5 is moved into contact with the roller 14 of the trip-member 12. Subsequent movement tends to move the trip 12, but movement of the latter is resisted by means of the stop 16 bearing against the lug portion 27 of the weighted lever 24. It will be obvious, however, 25 that the resistance offered by this weighted lever 24 is of a yielding character and that should the pressure exerted on the trip be substantially great the weighted lever 24 would yield, as clearly indicated in Fig. 3 of the drawing, until such time as the great pressure shall have been relieved. If the star-wheel 5 for any reason resists rotation or "tripping" and the weighted lever 24 yields to permit movement of the trip 12 30 out of the path of the star-wheel, the parts will be restored to their normal positions by gravity, it being noted that the finger 18 is sufficiently short to swing by the lug 27 and that the finger 21 is pivotally mounted and adapted to click or wipe by said stud. When it is desired to rotate the spider 2 in a direction opposite to that indicated by the arrow in Fig. 1, the trip 12 is merely pushed out of the path of travel of the star-wheel. A collar 28 is adjustably fixed on the shaft 11 by means of a set-screw and operates with the stop 16 to hold the shaft 11 against longitudinal movement in the support 10. The slots 9 are elongated and 45 permit the vertical adjustment of the trip and stop. By loosening the set-screws 15, 17 and 29 horizontal adjustment of either the trip or the stop, or both of them, may be secured.

50. It will be seen from the foregoing that a device is provided which accomplishes, among others, all the objects and advantages hereinbefore set forth, and one which is devoid of springs or delicate instrumentalities.

60. As many changes could be made in the above construction and many apparently widely different embodiments of this invention could be made without departing 65 from the scope thereof, it is intended that

all matter contained in the above description or shown in the accompanying drawing shall be interpreted as illustrative and not in a limiting sense.

Having described my invention, what I claim as new and desire to secure by Letters Patent is:

1. In dyeing apparatus or the like, in combination, a yarn stick carrying device, means associated with said device adapted to cause rotation of a yarn stick carried thereby, a trip member adapted to co-act with said last means, and gravity controlled means adapted to yield upon the application of unusual pressure whereby movement of said trip member is resisted to cause tripping.

2. In dyeing apparatus or the like, in combination, a yarn stick carrying device, means associated with said device adapted to cause rotation of a yarn stick carried thereby, a trip member adapted to co-act with said last means, gravity controlled means adapted to yield upon the application of unusual pressure whereby movement of said trip member is resisted to cause tripping, and regulating means whereby said trip member may be caused to resist different degrees of unusual pressure.

3. In dyeing apparatus or the like, in combination, a trip member, means comprising a weight adapted to yield upon the application of unusual pressure whereby movement of said trip member is resisted, and regulating means whereby said trip member may be caused to resist different degrees of pressure.

4. In dyeing apparatus or the like, in combination, a trip member, means adapted to yield upon the application of unusual pressure whereby movement of said trip member is resisted, means whereby movement of said trip member in an opposite direction is permitted, and regulating means whereby said trip member may be caused to resist different degrees of unusual pressure.

5. In dyeing apparatus or the like, in combination, a trip member, a weighted lever adapted to yield upon the application of unusual pressure whereby movement of said trip member is resisted, and regulating means whereby said trip member may be caused to resist different degrees of unusual pressure.

6. In dyeing apparatus or the like, in combination, a trip member, a weighted lever adapted to yield upon the application of unusual pressure whereby movement of said trip member is resisted, means whereby movement of said trip member in an opposite direction is permitted, and regulating means whereby said trip member may be caused to resist different degrees of unusual pressure.

7. In dyeing apparatus or the like, in combination, a support, a trip member pivotally arranged thereon, a stop member fixed relatively to said trip member and pivotally movable relative to said support, and a second stop member co-acting with said first stop member comprising a pivoted lever having a weight. 5
8. In dyeing apparatus or the like, in combination, a support, a trip member pivotally arranged thereon, a stop member fixed relatively to said trip member and pivotally movable relative to said support, a second stop member co-acting with said first stop member comprising a pivoted lever having a weight, and means whereby said weight and lever may be relatively adjusted to position said weight at different points away from the pivot point of said lever. 10
9. In dyeing apparatus or the like, in combination, a yarn stick carrying device, means associated with said device adapted to cause rotation of a yarn stick carried thereby, a trip member with which said last means is adapted to contact, means adapted to yield upon the application of unusual pressure whereby movement of said trip member is resisted, and regulating means whereby said trip member may be caused to resist different degrees of unusual pressure. 15
10. In dyeing apparatus or the like, in combination, a yarn stick carrying device, means associated with said device adapted to cause rotation of a yarn stick carried thereby, a trip member with which said last means is adapted to contact, means adapted to yield upon the application of unusual pressure whereby movement of said trip member is resisted, means whereby movement is permitted of said trip member by said stop member in an opposite direction, and regulating means whereby said trip member may be caused to resist different degrees of unusual pressure. 20
11. In dyeing apparatus or the like, in combination, a yarn stick carrying device, means associated with said device adapted to cause rotation of a yarn stick carried thereby, a trip member with which said last means is adapted to contact, a stop member relatively fixed to said trip member, and a movable stop member co-acting with the first said stop member and comprising a pivoted lever and a weight and normally held by gravity in position to resist movement of said trip member. 25
12. In dyeing apparatus or the like, in combination, a support, a trip member pivotally mounted on one side of said support, a stop member fixed relatively to said trip member on the other side of said support, and a co-acting stop member pivoted relatively to said support and controlled by gravity to resist movement of said first stop member. 30
13. In dyeing apparatus or the like, in combination, a support, a trip member pivotally mounted on one side of said support, a stop member fixed relatively to said trip member on the other side of said support and comprising a pivotally movable contacting member braced against movement in one direction and freely movable in the opposite direction, and a co-acting stop member pivoted relatively to said support and controlled by gravity to resist movement of said first stop member. 35
14. In dyeing apparatus or the like, in combination, a support, a trip member pivotally mounted on one side of said support and adapted for rolling contact with a star-wheel, a stop member fixed relatively to said trip member on the other side of said support, and a co-acting stop member pivoted relatively to said support and disposed by gravity to resist movement of said first stop member. 40
15. In dyeing apparatus or the like, in combination, a support, a trip member pivotally mounted on one side of said support and adapted for rolling contact with a star-wheel, a stop member fixed relatively to said trip member on the other side of said support and comprising a pivotally movable contacting member braced against movement in one direction and freely movable in the opposite direction, and a co-acting stop member pivoted relatively to said support and disposed by gravity to resist movement of said first stop member. 45
16. In dyeing apparatus or the like, in combination, a yarn stick carrying device, means movable with said device adapted to cause rotation of a yarn stick, a trip member adapted to be disposed in the path of said means, and means comprising a gravity controlled device adapted to resist movement of said trip member in one direction. 50
17. In dyeing apparatus or the like, in combination, a yarn stick carrying device, means movable with said device adapted to cause rotation of a yarn stick, and a trip member arranged to be moved by gravity into the path of said means. 55
18. In dyeing apparatus or the like, in combination, a yarn stick carrying device, means movable with said device adapted to cause rotation of a yarn stick, and a pivoted trip member arranged to be moved by gravity into the path of said means. 60
19. In dyeing apparatus or the like, in combination, a yarn stick carrying device, means movable with said device adapted to cause rotation of a yarn stick, and a trip member adapted to be disposed in the path of said means and arranged to gravitatively resist passage of said means. 65
20. In dyeing apparatus or the like, in combination, a yarn stick carrying device, means movable with said device adapted to 70
- 75
- 80
- 85
- 90

cause rotation of a yarn stick, and a pivoted trip member adapted to be disposed in the path of said means and arranged to gravitatively resist passage of said means.

5 21. In dyeing apparatus or the like, in combination, a yarn stick carrying device, means movable with said device adapted to cause rotation of a yarn stick, a trip member arranged to be moved by gravity into 10 the path of said means, and means comprising a gravity controlled device adapted to resist movement of said trip member in one direction.

22. In dyeing apparatus or the like, in 15 combination, a yarn stick carrying device, means movable with said device adapted to cause rotation of a yarn stick, a trip member arranged to be moved by gravity into the path of said means, and means comprising a gravity controlled device adapted to resist movement of said trip member in one direction, said trip member having a relatively movable stop adapted to move said gravity controlled device when the trip 25 member is moved in one direction, and to wipe past said gravity controlled device when said trip member moves in the opposite direction.

23. In dyeing apparatus or the like, in 30 combination, a yarn stick carrying device, means movable with said device adapted to cause rotation of a yarn stick, a pivoted trip member arranged to be moved by gravity into the path of said means, and means comprising a gravity controlled device adapted 35 to resist movement of said trip member in one direction.

24. In dyeing apparatus or the like, in 40 combination, a yarn stick carrying device, means movable with said device adapted to cause rotation of a yarn stick, a trip member arranged to be moved by gravity into the path of said means, and means comprising a gravity controlled device adapted 45 to resist movement of said trip member in one direction, said trip member having a pivoted stop adapted to move said gravity controlled device when the trip member is

moved in one direction, and to wipe past said gravity controlled device when said trip member moves in the opposite direction. 50

25. In dyeing apparatus or the like, in combination, a yarn stick carrying device, means movable with said device adapted to cause rotation of a yarn stick, a pivoted 55 trip member arranged to be moved by gravity into the path of said means, and means comprising a gravity controlled device adapted to resist movement of said trip member in one direction, said trip member having a pivoted stop adapted to move said gravity controlled device when the trip member is moved in one direction, and to wipe past said gravity controlled device when said trip member moves in the opposite direction. 60

26. In dyeing apparatus or the like, in combination, a yarn stick carrying device, means movable with said device adapted to cause rotation of a yarn stick, a trip member arranged to be moved by gravity into 70 the path of said means, and means comprising a pivoted gravity controlled device adapted to resist movement of said trip member in one direction.

27. In dyeing apparatus or the like, in 75 combination, a yarn stick carrying device, means movable with said device adapted to cause rotation of a yarn stick, a pivoted trip member arranged to be moved by gravity into the path of said means, and means comprising a pivoted gravity controlled device 80 adapted to resist movement of said trip member in one direction, said trip member having a pivoted stop adapted to move said gravity controlled device when the trip member is moved in one direction, and to wipe past said gravity controlled device when said trip member moves in the opposite direction.

In testimony whereof I affix my signature, 85 in the presence of two witnesses.

WILLIAM W. BROWN.
